SAFETY DEVICE FOR HEATING AND OTHER APPARATUS

Guido Wünsch, Berlin-Steglitz, and Josef Schuppert, Dessau, Germany, assignors to Askania-Werke A. G. vormals Central Werkstatt Dessau und Carl Bamberg-Friedenau, a German company

Application August 3, 1934, Serial No. 738,370
In Germany September 28, 1933

10 Claims. (Cl. 158—117.1)

This invention relates to safety devices for heating and other apparatus.

One of the main objects of the present invention is to provide a combined thermocouple and pilot burner which is effective and reliable in operation and, at the same time, constitutes a relatively simple and compact unitary device, with the thermocouple means maintained in the desired relation with respect to the pilot burner.

Another and more specific object of the invention is to provide a thermocouple and pilot burner comprising a jet member having port means through which fuel is discharged to maintain a pilot flame, there being a fuel supply pipe connected to the jet member, and a plurality of thermocouples disposed at circumferentially spaced locations about the jet member, each of the thermocouples comprising a pair of thermocouple elements joined at their outer ends to form a plurality of circumferentially disposed thermal junctions adapted to be heated by the pilot flame, and the device having insulating means surrounding the jet member and insulating the thermocouple elements of each thermocouple from each other and at least one thermocouple element of each thermocouple from the jet member and means for clamping the thermocouples and insulating means in place upon the jet member so that the parts constitute a unitary device with the plurality of thermal junctions adapted to be heated by the pilot flame maintained in substantially corresponding relation to said flame at circumferentially spaced positions.

Another object of the invention is to provide in a thermocouple and pilot burner of the class described shield means constituting a unitary part of the device and cooperating with the pilot flame to assure heating of all of the thermal junctions at the outer ends of the thermocouples.

Another object is to provide an improved form of thermocouple unit.

Further objects and advantages of the present invention will appear from the following detailed description, taken in connection with the accompanying drawings, in which:

Fig. 1 is a diagrammatic view partly in section of one illustrative embodiment of the invention; and

Figs. 2 to 5 show various illustrative arrangements of the thermocouple means relative to the igniting means or pilot;

In the following description the invention will be described in its application to heating apparatus, and more particularly to liquid heating

apparatus, but it will be apparent to those skilled in the art that broadly the invention is equally applicable to other apparatus in which the use of a safety device is indicated.

Referring to Fig. 1 the invention is therein shown in its application to heating apparatus using gas as a heat generant. The gas may be supplied from any suitable conventional source of supply (not shown) to a burner or burners 2 through a suitable, passage herein, comprising pipes 4 and 6 communicating through a valve seat opening 8 with which cooperates a valve 10. Suitable igniting means, herein a pilot 26 issuing from a burner 24 is provided to ignite the gas from the main burner 2. Controlling means for said valve 10 is also provided, said controlling means being preferably heat-responsive so as to be controllable by said pilot or other heating or igniting means. Herein said valve-controlling means will preferably comprise a magnet and thermocouple 22. Said magnet will conveniently be a pot-shaped magnet 12 supported by the upper wall of pipe 4 and over said valve 10 which will conveniently comprise the armature of said magnet, said valve being preferably made as light as possible. The core 14 and sleeve 16 of said magnet may be integral and will preferably be made of iron having a very low capacity for residual magnetism. An iron alloy containing over 30% of nickel satisfies this condition. The magnet winding 18 will preferably be of quite thick copper wire, 2 mm. or more in diameter. One end of said winding is conductively connected to said magnet while the other end is connected, preferably by a quite thick copper wire 20, with one terminal of a thermocouple 22. The other terminal of said thermocouple is herein conductively connected to said burner 24 of said gas pilot 26 to which gas is supplied through a pipe 28 connected to the gas supply, 40 said pipe being herein conveniently connected to the pipe 6 and between said valve seat 10 and the main burner 2. Said terminal is thus conductively connected to said magnet through the walls of pipes 28, 6 and 4. The thermocouple 22 is so positioned relatively to said pilot that junctions or points of union thereof are heated by said pilot. As more fully explained hereinafter one or more thermocouples may be used.

The valve spindle 30 extends through a bearing 32 in the lower wall of said pipe 6 and carries a disk 34 at its free end. The latter is contained in a cylinder 36 also containing a piston 38. This piston carries a central boss 40 supporting a helical spring 42 below said disk 34 and pref-

erably out of contact with the latter when said valve 10 is in raised position. The rod 44 of said piston extends through the lower end wall of said cylinder 36 and its free end is connected to a plug 46 having a sliding fit in the cylinder part 48. A helical spring 49 surrounds said rod 44, one end thereof engaging the bottom of said plug and the other the end wall of said cylinder 36, said spring thus tending to press said piston 10 38 downwardly.

It will be apparent that by pressing upwardly upon the lower end of the plug 46 the piston 38 will be raised, and if the valve 10 has dropped continued pressure on said plug will raise said 15 valve 10 into position to be attracted by said magnet.

Preferably damping or retarding means will be provided in accordance with the invention to retard downward movement of the piston 38 20 when it has been thus raised. Herein said retarding means comprises a port 50 opening through the lateral wall of said cylinder 36 into a chamber 52 containing a disk 54 and a helical spring 56, one end of which engages said disk 25 and the other end the opposite wall of said chamber and thus tends to press said disk against said port. Said disk is provided with a small throttling or choke port 58, the whole thus forming a non-return valve.

30 The operation of the construction so far described is as follows: The valve 10 being in open position and against the magnet 12 as shown in Fig. 1, it will be maintained in that position so long as the pilot 26 remains ignited, as the thermo-electric current engendered by the heating of the thermocouples 22 by said pilot energizes said magnet. Gas thus flows freely through the valve seat 8 to the burner 2 and will be thereby ignited by said pilot. Should said pilot 26 become extinguished for any reason, the thermocouples will quickly cool, the thermo-electric current will cease and the magnet being thus de-energized, the valve 10 will drop and close the valve seat opening 8 thus cutting off the gas supply to the 40 burner 2 and pilot 26.

To light said burner 2, plug 46 is pressed upwardly thus raising the piston 38. The air in cylinder 36 being thus compressed the disk 54 will be raised from the port 50 against the tension of spring 56 and air will thus escape from said cylinder through said port 50. Before said piston 38 will have reached its highest position, spring 42 will have engaged said disk 54 and raised said valve 10 from its seat and into contact with 55 said magnet 12. In thus raising said valve said spring 42 will be compressed, so that in the highest position of said valve said spring 42 will be tensioned between the disk 54 and piston 38.

The burner 2 and pilot being now supplied 60 with gas can be lighted. The pilot then heats said thermocouples 22 thus energizing said magnet which will maintain the valve 10 open so long as said pilot is lighted. Even should plug 46 be immediately released after raising said valve, 65 spring 42 will continue to hold said valve in contact with said magnet until the latter becomes sufficiently energized to hold it there, for as previously exhausted air from cylinder 36 can re-enter the same only very slowly through said 70 throttling port 58 in disk 54, piston 38 can drop only very slowly. Consequently before the compressed spring 42 can expand sufficiently to allow said valve 10 to drop, the thermo-electric current will have become sufficiently strong to hold 75 valve 10 in open position.

The pilot or other igniting or heating means and the thermo-couples should be relatively positioned so that junctions or points of union of said thermocouples shall be well and reliably heated.

Fig. 2 shows two parallel thermocouples 80 and 82 having their points of union at opposite sides of the pilot flame and close to its edge. The two metal wires forming each of said two thermocouples are connected respectively to two annuli 84 and 86 of which the latter forms a clamping sleeve. One of the elements of each of said thermocouples, wires 88 and 90 for example, made preferably of constantan, are connected to said clamping sleeve 86, the other elements of each of said thermocouples, copper wires or better still silver wires 92 and 94 are connected to said annulus 84. The parts are assembled by sliding the annulus 84 over the burner 96, placing an insulating sleeve 98 over said annulus 84 and then sliding said clamping sleeve or annulus 86 over said insulating sleeve. A clamping screw 100 has screw-threaded engagement with parallel ears 104-106 formed at the ends of said sleeve 86 and serves removably to clamp the parts upon said burner 96. Thermocouple elements 92 and 94 are conductively connected to one end of the magnet winding through annulus 84 and pilot burner 96, while thermocouple elements 88 and 90 are conductively connected to the other end of said magnet winding through said clamping sleeve or annulus 86 and a suitable conductor 102 for example, clamped in contact with said sleeve by said clamping screw 100. The arrangement described has the advantage that the thermocouples can always be readily removed and assembled.

Similar arrangements are shown in Figs. 3 to 5. In these, however, a plurality of thermocouples 80, 88 and 82, 86 are shown having their junctions or points of union interconnected, for example by a ring 108 which may be of one of the metals forming the thermocouples, of silver for example.

In Figs. 3, 4 and 5 the pilot flame or other igniter or heater means will extend through the ring 108 whereby the points of union will be uniformly heated. Proper heating of the points of union of the thermocouples is assured, even in case of deflection of the gas jet by drafts or other causes. Fig. 4 shows in perspective how the ring 108 may be reinforced in cross section to give it greater strength.

The thermo-elements, built according to Figs. 5 and 8, have their hot junctions considerably smaller than the opposite junctions formed by the elements 86, 88 and 90. The ring 86 is, of course, also heated if the pilot flame burns, but to a smaller extent than the hot junctions which are directly exposed to the flame. If the pilot flame is extinguished, its junctions which were directly exposed to the flame will cool off considerably faster than the other junctions, due to the lower heat capacity thereof in comparison to the ring 86 which has a considerably larger heat capacity. The previously relatively cold junctions will therefore remain hot longer than the previously heated hot junctions. Consequently, a thermo-current in the reverse direction will be produced when the temperature difference between the two junctions is reversed. This thermo-current in the opposite direction has a tendency to energize the electromagnet in a reverse manner and thereby overcome or practically eliminate the residual magnetism therein,

so that the valve control will be permitted to drop practically instantaneously. This is a very important advantage of the invention.

It is to be understood that the present invention may be embodied in other specific forms without departing from the spirit or essential attributes of said invention, and it is therefore desired that the present embodiments be considered in all respects as illustrative and not restrictive, reference being had to the appended claims rather than to the foregoing description to indicate the scope of the invention.

We claim:

1. In combination, a burner for maintaining a flame, an electromagnet having a magnet frame and a winding, a thermocouple comprising dissimilar thermocouple members connected to the winding of said electromagnet and joined to form a hot junction positioned at the edge of the flame to be heated thereby, and an annulus conductively connected to said thermocouple members at the hot junction thereof and encircling the flame maintained by said burner to assure adequate heating of the hot junction of the thermocouple when the flame is diverted by drafts.

2. In combination, a burner for maintaining a flame, an electromagnet having a magnet frame and a winding, a thermocouple comprising a plurality of dissimilar thermocouple members connected to the winding of said electromagnet and joined to form a plurality of hot junctions positioned at circumferentially spaced positions about the edge of the flame to be heated thereby, and an annulus conductively connected to said thermocouple members at the hot junctions thereof and encircling the flame maintained by said burner to assure adequate heating of the hot junctions of the thermocouple when the flame is diverted by drafts.

3. In combination, a burner for maintaining a flame, a fuel supply pipe leading to said burner, an electromagnet having a magnet frame and a winding, a thermocouple comprising a pair of thermocouple members joined to form a thermal junction in position to be heated by the flame, one of said thermocouple members being conductively connected to the fuel supply pipe for the burner and through said fuel supply pipe to the winding of the electromagnet, means connecting the other thermocouple member to the electromagnet winding, said thermocouple members being joined to form a hot junction at the edge of the flame maintained by said burner, and an annulus conductively connected to said thermocouple members at the hot junction thereof and encircling the flame maintained by said burner to assure adequate heating of the hot junction of the thermocouple when the flame is diverted by drafts.

4. In combination, a burner for maintaining a flame, a fuel supply pipe leading to said burner, an electromagnet having a magnet frame and a winding, an annulus telescopically fitting over the burner and in conductive contact therewith, a conducting member surrounding said annulus and insulated therefrom, a thermocouple comprising a pair of thermocouple members joined to form a thermal junction in position to be heated by said flame, one of said thermocouple members being conductively connected to said annulus and to the winding of the electromagnet through said annulus, the burner and the fuel supply pipe therefor, and the other thermocouple member being conductively connected to the conducting member surrounding said annulus.

conducting member surrounding said annulus and through said conducting member to the winding of the electromagnet.

5. In combination, a burner for maintaining a flame, a fuel supply pipe leading to said burner, an electromagnet having a magnet frame and a winding, an annulus telescopically fitting over the burner and in conductive contact therewith, a conducting member surrounding said annulus and insulated therefrom, a thermocouple comprising a pair of thermocouple members joined to form a thermal junction in position to be heated by said flame, one of said thermocouple members being conductively connected to said annulus and to the winding of the electromagnet through said annulus, the burner and the fuel supply pipe therefor, the other thermocouple member being conductively connected to the conducting member surrounding said annulus and through said conducting member to the winding of the electromagnet, and a second annulus conductively connected to said thermocouple member at the hot junction thereof and encircling the flame maintained by said burner to assure adequate heating of the hot junction of the thermocouple when the flame is diverted by drafts.

6. A self-contained thermocouple and pilot burner unit comprising a plurality of circumferentially spaced thermocouples, each comprising a pair of thermocouple elements joined at their outer ends to form a plurality of circumferentially disposed thermal junctions, a jet member joined to said thermocouples to form a unitary device having the desired relation between said jet member and the thermal junctions at the outer ends of said thermocouples, said jet member extending substantially axially between said circumferentially disposed thermocouples and having port means at its outer end through which fuel is discharged to maintain a pilot flame for use as an igniter, and shield means constituting a unitary part of the device and cooperating with the pilot flame to assure heating of all of the thermal junctions at the outer ends of said thermocouples.

7. A thermocouple and pilot burner unit comprising a jet member having port means through which fuel is discharged to maintain a pilot flame, a fuel supply pipe connected to said jet member, a plurality of thermocouples disposed at circumferentially spaced locations about said jet member, each of said thermocouples comprising a pair of thermocouple elements joined at their outer ends to form a plurality of circumferentially disposed thermal junctions adapted to be heated by the pilot flame, insulating means surrounding said jet member and insulating the thermocouple elements of each thermocouple from each other and at least one thermocouple element of each thermocouple from said jet member, and means for clamping said thermocouples and insulating means in place upon said jet member so that the parts constitute a unitary device with the plurality of thermal junctions adapted to be heated by the pilot flame maintained in substantially corresponding relation to said flame at circumferentially spaced positions by the clamping of said thermocouples and insulating means in place upon said jet member.

8. A thermocouple and pilot burner unit comprising a jet member having port means through which fuel is discharged to maintain a pilot flame, a fuel supply pipe connected to said jet

- member, a plurality of thermocouples disposed at circumferentially spaced locations about said jet member, each of said thermocouples comprising a pair of thermocouple elements joined at their outer ends to form a plurality of circumferentially disposed thermal junctions adapted to be heated by the pilot flame, insulating means surrounding said jet member and insulating the thermocouple elements of each thermocouple 5 from each other and at least one thermocouple element of each thermocouple from said jet member, means for clamping said thermocouples and insulating means in place upon said jet member so that the parts constitute a unitary 10 device with the plurality of thermal junctions adapted to be heated by the pilot flame maintained in substantially corresponding relation to said flame at circumferentially spaced positions by the clamping of said thermocouples and insulating means in place upon said jet member, and shield means constituting a unitary part of said device and cooperating with the pilot flame to assure heating of all of the thermal junctions 15 at the outer ends of said thermocouples.
- 20 9. A thermocouple and pilot burner comprising a jet member having port means at its outer end through which fuel is discharged to maintain a pilot flame, a fuel supply pipe connected to said jet member, sleeve means surrounding said jet member and mounted thereon, and a plurality of thermocouples carried by said sleeve means and disposed at circumferentially spaced 25 locations about said jet member, each of said thermocouples comprising a pair of thermo-

couple elements joined at their outer ends to form a plurality of circumferentially disposed thermal junctions adapted to be heated by the pilot flame, the thermocouple elements of each thermocouple being insulated from each other 5 and at least one thermocouple element of each thermocouple being insulated from said jet member.

10. A thermocouple and pilot burner comprising a jet member having port means at its outer 10 end through which fuel is discharged to maintain a pilot flame, a fuel supply pipe connected to said jet member, sleeve means surrounding said jet member and mounted thereon, a plurality of thermocouples carried by said sleeve 15 means and disposed at circumferentially spaced locations about said jet member, each of said thermocouples comprising a pair of thermocouple elements joined at their outer ends to form a plurality of circumferentially disposed 20 thermal junctions adapted to be heated by the pilot flame, the thermocouple elements of each thermocouple being insulated from each other and at least one thermocouple element of each thermocouple being insulated from said jet member, 25 and shield means carried by said jet member and constituting a unitary part of said device, said shield means cooperating with the pilot flame to confine same and assure heating of all of the circumferentially disposed thermal 30 junctions at the outer ends of said thermocouples.
